PLASTIC SNAP HINGE

René P. Magnenat, Waterbury, Conn., assignor to
 Waterbury Companies, Incorporated, Water-
 bury, Conn., a corporation of Connecticut

Application October 14, 1949, Serial No. 121,337

4 Claims. (Cl. 220—31)

1

This invention relates to a hinge structure for receptacles having swingable covers of molded plastic material, and more particularly to a hinge structure having a double-acting spring which is adapted to urge the receptacle cover selectively either to open or closed position with a snap action.

One object of this invention is to provide a device of the above nature in which the spring will serve both for swinging the cover and for holding the cover in assembled relation with the base of the receptacle.

Another object is to provide a receptacle in which the edges of the cover and the base have auxiliary interengagable means for holding the hinge connection assembled when the cover is in closed position.

A further object is to provide a device of the above nature which will be simple in construction, inexpensive to manufacture, easy to assemble and manipulate, compact, ornamental in appearance, and very efficient and durable in use.

With these and other objects in view, there have been illustrated on the accompanying drawing two forms in which the invention may conveniently be embodied in practice.

In the drawing,

Fig. 1 is a plan view of a receptacle embodying the first form of the improved plastic snap hinge, and showing the cover in closed position.

Fig. 2 is a side view of the same.

Fig. 3 is a front view of the same.

Fig. 4 is a cross sectional view on an enlarged scale, taken on the line 4—4 of Fig. 1.

Fig. 5 is a fragmentary perspective view on a still larger scale, showing the hinge structure partly in section.

Fig. 6 is a cross sectional view, similar to a portion of Fig. 4, but showing the hinge structure as it would appear with the cover open.

Fig. 7 is a fragmentary perspective view showing a second form of the improved snap hinge.

Referring now to the drawings in which like reference numerals denote corresponding parts throughout the several views, the numeral 10 indicates a receptacle base having a flat bottom wall 11 and a peripheral wall 12, and the numeral 13 indicates a cover having a top wall 14 and a peripheral wall 15. The outlines of the base 10 and the cover 13 are of the same general size and shape, so that when the cover 13 is closed the peripheral wall 15 will be disposed in aligned abutting relationship with the peripheral wall 12 of the base 10.

A portion of the peripheral wall 12 at the rear 55

2

of the base 10 is outwardly offset so as to provide an inwardly concave bracket portion 16, the upper side portions of which are curved forwardly in tangent relationship to the upper edge of the wall 12, so as to provide short bearing flanges 17, 18 separated by a rectangular slot 19 in the upper edge of the bracket portion 16.

The rear of the peripheral cover wall 15 is provided with an integral depending lug 20 which has a substantially cylindrical surface curvature, and which is of suitable dimensions to close the slot 19 in all normal positions of the cover 13.

The lug 20 has a pair of reduced cylindrical side trunnions 21, 22 which are adapted to underlie and be retained in position against the lower surfaces of the bearing flanges 17, 18, so that the cover 13 may swing about said trunnions 21, 22 from the closed position shown in Fig. 4, to the open position indicated in Fig. 6.

The cylindrical lug 20 is preferably provided with an outer horizontal projecting shoulder or abutment 23 which is adapted to engage the lower end of the slot 19, and thus serve as a stop to limit opening movement of the cover 13.

In order to retain the trunnions 21, 22 against the flanges 17, 18, provision is made of a U-shaped wire spring 24 having a straight horizontal central section 25 engaged in a longitudinal slot 26 in the lower surface of the lug 20. The sides of the U-shaped wire spring 24 comprise a pair of upwardly concave side arms 27, 28 which terminate at their lower ends in aligned outturned portions 29, 30.

In order to anchor the outturned ends 29, 30 of the U-shaped spring 24, the interior of the receptacle base 10 is integrally provided with raised bosses 31, 32 extending forwardly from the peripheral wall 12 at opposite sides of the bracket wall portion 16. The upper surfaces of the bosses 31, 32 are formed with respective aligned open-topped grooves 33, 34, in which the outturned spring ends 29, 30, are received, and which are so located as to hold the U-shaped spring 24 in a compressed condition in which the curved spring side arms 27, 28 are resiliently bent.

It will be noted that the parts are so arranged that the slot 26 is disposed at the lowermost portion of the cylindrical lug 20 when the cover 13 is in horizontal or closed position, while the axis of the trunnions 21, 22 is so disposed above said slot 26 that a plane including said axis and the grooves 33, 34 is inclined at an angle of approximately 45 degrees to the horizontal.

Thus, the U-shaped wire spring 24 will not

only hold the trunnions 21, 22 in engagement with the bearing flanges 17, 18 when the cover 13 is closed, but will also provide a toggle action urging said cover 13 either to closed or to open position, depending upon the position of said cover in its swinging movement. For example, the compressive force of the spring 24 will tend to hold the cover 13 open when said cover is in the position shown in Fig. 6, while the cover will be held closed when in the position shown in Fig. 4.

In order to provide additional detent means for holding the trunnions 21, 22 in engagement with the bearing flanges 17, 18 when the cover 13 is in closed position, the lower front edge of said cover is provided with a depending nose 35 which is adapted to engage in a corresponding recess 36 in the front of the receptacle base 10.

Thus, accidental separation or misalignment of the cover 13 with the base 10 will positively be prevented while said cover is in closed position.

When the cover 13 is open, as shown in Fig. 6 for example, separation of the trunnions 21, 22 from the bearing flanges 17, 18 will be positively prevented by virtue of the fact that lower edge portions of the peripheral wall 15 will overlie the outer downwardly curved surfaces of the bearing flanges 17, 18.

In order to accommodate and to conceal the lug 35 and the recess 36 at the front of the receptacle, the base 10 and cover 13 preferably have complementary outer bosses 37, 38. Provision is also made of relatively small lateral bosses 39, 40, which extend to the left of the boss 38, and the right of the boss 37, respectively, in order to serve as finger pieces for facilitating the opening of the receptacle.

Assembly of first form

In assembly, the cover 13 will be brought toward the receptacle base 10 in a position forwardly offset from the final assembled position of said cover, and sufficiently separated from the front of the base 10 to enable the nose 35 to clear the upper edge of the boss 37.

In this offset position the trunnions 21, 22 will be disposed just forwardly of the bearing flanges 17, 18, and said trunnions may now be slid under said flanges merely by pressing the cover 13 rearwardly with respect to the base 10. The cover 13 will now be opened to the position shown in Fig. 6, and the outturned end portions 29, 30 of the spring 24 will be inserted in the grooves 33, 34.

The straight central section 25 of the spring 24 will then be pressed downwardly over the surface of the cylindrical lug 20, until said central section snaps into the slot 26, whereupon assembly will be complete.

The cover 13 may now be closed by swinging it downwardly, this action resulting in compression of the spring 24 until such time as the straight spring section 25 has passed the dead center position in which the cover 13 is disposed at approximately 45 degrees to the base 10.

The tendency of the curved spring arms 27, 28 to straighten will then cause the spring 24 to expand, thus urging the cover 13 to the completely closed position shown in Fig. 4.

When the cover 13 is in closed position, the nose 35 will be interengaged with the recess 36, thus holding the cover 13 aligned with the base 10 and positively preventing separation of the trunnions 21, 22 from the bearing flanges 17, 18.

One advantage of the first form of the invention is that the curved shape of the spring arms 27, 28 will afford clearance for objects which may be contained within the box.

Second form

In the second form of the invention shown in Fig. 7, the structure is substantially the same as in the first form excepting for the specific spring and the modification of the lug to accommodate said spring.

In the second form, provision is made of a wire spring 41 in the form of a broad U which is disposed entirely in a single plane and which comprises a short straight central section 42 and straight diverging side arms 43, 44 having outturned terminal portions 45, 46, the latter being received in the grooves 33, 34 in the bosses 31, 32 of the base 10.

The peripheral cover wall 15 is provided with a modified, generally cylindrical depending lug 47, the lower portion of which has flattened segmental end zones 48, 49, thus providing a downward central projection 50 of approximately the same length as the central spring section 42.

The central spring section 42 is disposed in a longitudinal slot 51 in the lower surface of the lug projection 50, so that the spring arms 43, 44 will be disposed at the end zones 48, 49 and will be swingable at opposite ends of the projection 50.

Assembly of second form

In assembly, the trunnions 21, 22, will be slid under the bearing flanges 17, 18, and the cover 13 will then be opened, as in the assembling of the first form of the invention. The terminal portions 45, 46 of the spring 41 will then be placed in the grooves 33, 34, respectively, and the central spring section 42 will be brought

against the surface of the lug projection 50 and pressed downwardly until it snaps into the slot 51, whereupon the hinge structure will be completely assembled, and the box cover 13 may be repeatedly opened and closed as desired.

The "dead center" position of the cover 13 will occur when said cover is disposed at approximately 45 degrees to the base 10, the diverging relationship of the spring arms 43, 44 permitting the spring 41 to bend and be compressed in this position of the cover 13. Thus, it will be seen that the assembly and operation of the second form of the invention will be substantially the same as the assembly and operation of the first form.

One advantage of both forms of the improved hinge structure herein disclosed is its ease of assembly, whereby the receptacles embodying said hinge structure may be very economically manufactured.

While there have been disclosed in this specification two forms in which the invention may be embodied, it is to be understood that these forms are shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a container, the combination comprising a base constructed of molded plastic material,

a peripheral wall integral with and upstanding from said base, said peripheral wall comprising a rearwardly off-set bracket portion having a slot in its upper edge, a molded plastic cover for said base comprising a depending lug disposed within said slot, said bracket portion extending forwardly at opposite sides of said slot to provide a pair of short flanges having downwardly and forwardly facing horizontal bearing surfaces, a pair of aligned trunnions integral with opposite ends of said depending lug and underlying said bearing surfaces, a shallow substantially U-shaped spring within said container having opposed outwardly projecting end portions, means centrally located at the outer end of said depending lug and off-set from said trunnions for holding the central portion of said spring, and means within said base and aligned with and forward of said first spring retaining means for constraining the outwardly projecting end portions of said spring against inward movement with respect to said base without interfering with sidewise expansion of said end portions, whereby said spring will have a snap toggle action urging said cover selectively toward open and closed positions.

2. The invention as defined in claim 1 in which

a rear portion of said depending lug is provided with a stop shoulder adapted to abut the lower end of said slot for limiting opening movement of said cover.

3. The invention as defined in claim 1 wherein all portions of said spring lie substantially in a single plane.

4. The invention as defined in claim 1 wherein the intermediate legs of said spring are outwardly convex.
